(57) **CLAIM**

I claim the ornamental design for a shackle, as shown and described.

DESCRIPTION

FIG. 1 is a perspective view of a shackle showing my new design;

FIG. 2 is another perspective view thereof;

FIG. 3 is a front elevational view thereof;

FIG. 4 is a top plan view thereof;

FIG. 5 is a right side elevational view thereof;

FIG. 6 is a left side elevational view thereof;

FIG. 7 is a rear elevational view thereof; and,

FIG. 8 is a bottom plan view thereof.

The broken lines, which define the bounds of the claimed design form no part thereof.

The broken lines environmental are for illustrative purpose only and form no part of the claimed design.
